UNITED STATES PATENT OFFICE

OTTO F. FOGELSTRAND, KENSINGTON, CONNECTICUT, ASSIGNOR TO HART
MANUFACTURING COMPANY, OF SAME PLACE.

DESIGN FOR A CUPBOARD-TURN.

Specification forming part of Design No. 5,498, dated January 30, 1872.

To all whom it may concern:

Be it known that I, OTTO F. FOGELSTRAND, of Kensington, in the county of Hartford and State of Connecticut, have invented and produced a new and original Design for a Cupboard-Turn, of which the following is a specification:

The nature of my design is fully represented in the accompanying engraving, to which reference is made.

A represents the body of the latch-case, and B the catch. On three sides of said parts is the plate or flange b. Surrounding the face of each of the parts A B b b is a plain ledge, a. The spaces inclosed by said ledge are mainly filled by fine check-work. On the flange b, above and below the case A, is a raised figure, c, consisting of scroll or ornamental work. On the flange b at the end of the case A is a

screw-hole, above and below which is a portion of a raised ornamental figure, d d, and a like figure is at the end of the catch B. The face of the latch-case A has two such figures, h h, one of which is partially hid by the knob C, and the face of the catch B has one, as shown. The face of the knob C is encircled by a raised ledge, inside of which is a raised star, whose points are tipped with diamonds. There is also a small figure of raised ornamental work between the several points of the star, as shown.

I claim as my invention—
The design for a cupboard-turn, as shown.
OTTO F. FOGELSTRAND.
